DOORCHECK

Wallace F. Moore, New Britain, Conn., assignor
to The American Hardware Corporation, New
Britain, Conn., a corporation of Connecticut

Application November 18, 1931, Serial No. 575,762

2 Claims. (Cl. 16—62)

My invention relates to door checks, and has for its object to provide a novel and improved door check which when mounted in the door and door casing is substantially concealed from view. Another of the objects of the invention is to provide a door check of the character indicated which is simple in construction, may be easily installed, and is efficient in operation.

The several features of the invention, whereby these and other objects may be attained, will be readily understood from the following description and accompanying drawings, in which:

Figure 1 is a view in perspective of a portion of a door and door casing having my improved check installed thereon;

Fig. 2 is a sectional plan view taken on the line 2—2 of Fig. 1 showing the door partly open;

Fig. 3 is a similar view showing the door closed;

Fig. 4 is a sectional view, on an enlarged scale, taken on the line 4—4 of Fig. 3;

Fig. 5 is a sectional view taken on the line 5—5 of Fig. 2; and

Fig. 6 is a sectional view taken on the line 6—6 of Fig. 5.

My improved door check is shown in the drawings installed on a door 2 and door casing 3. In the illustrated construction the check is provided with a piston chamber 4, a double headed piston 5, a rack 6 formed on the piston, a segmental pinion 8 operatively engaging the rack, a pinion shaft 10, a cylindrical chamber 12, surrounding the pinion shaft 10, a spiral spring 14 mounted in the chamber and operatively connected with the pinion shaft 10 through a ratchet wheel 13 and a pawl 15, and a spring actuated arm 16 secured on the upper end of the pinion shaft and carrying the pawl 15.

The piston chamber is provided with by-passes 18 associated with its ends, and valves 20 and 22 associated with each of the by-passes for controlling the flow of fluid in the piston chamber, the valve 20 being adapted to be adjusted to allow relatively fast closing of the door to near the latching point, whereupon its valve opening is closed by the head of the piston and the speed of the closing is slowed up to the latching point.

In accordance with the present invention, the casing of the check has a substantially rectangular portion having a substantially flat outer side 24, inner side 26 and end sides 28. The wall of the spring chamber is substantially cylindrical, and as shown substantially one-half thereof projects beyond the side 26 of the casing.

This projecting cylindrical portion has laterally projecting ears 30 near its lower end.

To install the check in the door, the upper edge thereof is mortised out to provide a recess 32 for receiving the projecting portion of the spring chamber 14 and the ears 30, with the side 26 of the casing on both sides of said projecting portion engaging flat against the inner side of the door. The check is held in place in the door by means of screws 34 extending through apertures in the ears 30 and screw-threaded into the lower end wall of the recess 32, and by screws 36 which extend through apertures in the ends of the rectangular portion of the check casing and screw-threaded into the door.

After the check is thus applied, a sheet metal casing or cover 38 is passed over the rectangular outer portion of the casing and is secured in place by screws 40 extending through apertures in flanges thereon. This cover closely fits the outer ends, top and bottom sides of the check casing, and is provided at its upper end with projecting portions 42 extending into the recess 32 and over the cover 41 of the spring chamber 14, said projecting portions 42 being spaced apart 20 to provide clearance of the ratchet wheel 13. The spring actuated arm 16 and pawl 15 extends over the upper wall of the cover 38. The outer side of the recess 32 is closed by a cover plate 44 which is secured by screws 45 to the door.

The connection between the spring actuated arm 16 and the door casing comprises a member 46 having projecting ears which receive the free end of said arm between them, and to which the end of the arm is pivotally connected. This member 46 is mounted to slide on a rod 50 which is arranged in a recess 52 in the upper horizontal portion of the door jamb, the ends of the rod being secured in bracket members 54 at the ends of said recess. The under side of the recess is 40 covered by a strip or plate 56 secured to the door casing by screws 58.

With this construction it will be apparent that when the door is closed the check is entirely concealed, the spring actuated arm 16 being contained within the recess 52, and the plain sheet metal cover 38 completely covering one side of the check, and the cover plate 44 covering the portion of the check contained within the recess 32. When the door is opened, the only part of 50 the check which is visible is a portion of the spring actuated arm 16 as shown in Figure 1.

With my improved check by arranging the by-passes 18 at an angle, and arranging the valves 20 and 22 vertically with their upper ends at the 55

upper side of the check casing as shown, when the sheet metal cover 38 is removed, the valves are conveniently accessible for adjustment to control the closing action of the door.

5 As will be evident to those skilled in the art, my invention permits various modifications without departing from the spirit thereof or the scope of the appended claims.

What I claim is:

- 10 1. In a door check, a check casing, a piston chamber in the casing horizontally arranged, a double headed piston within the chamber, means comprising a spring for operating the piston during the closing of the door, a chamber for the spring vertically arranged substantially mid-way between the ends of the casing, a by-pass associated with each end of the piston chamber inclined upwardly and outwardly with its lower end in communication with the piston chamber 15 at the rear of the associated piston head, said casing being provided with openings vertically arranged and in communication with the interior of the piston chamber and by-passes, there being two such openings associated with each end of 20 the chamber and being spaced at different distances from the end wall of the chamber, and a valve in each of said openings for controlling 25

communication between the interior of the piston chamber and the associated by-pass, the upper ends of said valves being accessible from the top side of the check casing.

2. In a door check of the type having a check casing forming a piston chamber horizontally arranged and a spring chamber vertically arranged above the piston chamber, a piston within the piston chamber, a spring in the spring chamber, a vertical shaft extending through the spring chamber connected with one end of the spring, connections between the lower end of said shaft and the piston for operating the piston, and a door closing arm secured to the upper end of said shaft, the improvement which consists in one side of the casing that forms the piston chamber being arranged substantially in the plane of the axis of said shaft and the opposite side of said portion of the casing being in a plane substantially tangent to the outer side of the wall of the spring chamber, and means for attaching the check to a door with said first mentioned side of the casing arranged against the side of the door and with the projecting portion of said spring chamber received in a recess in 25

WALLACE F. MOORE.
